Design No. 5,793, dated April 16, 1872.

UNITED STATES PATENT OFFICE.

ARCHIBALD McCALLUM, OF HALIFAX, ENGLAND, ASSIGNOR TO JOSEPH WILD & CO., OF NEW YORK, N. Y.

DESIGN FOR A CARPET-PATTERN.

Specification forming part of Design No. 5,793, dated April 16, 1872.

Specification describing a new and original Design for a Carpet, invented by ARCHIBALD McCALLUM, of Halifax, in the county of York, England.

This invention relates to two new ornamental figures used in carpets; and consists, first, in making one figure nearly circular, and in arranging within it two quarter-foils whose lines cross each other, as shown. The circular figure has small semicircular prominences.

The other figure is in form of a large quarter-foil containing an ornamental center, as shown.

I claim as my invention—

The design for a carpet containing the two ornamental figures, as shown.

ARCHIBALD McCALLUM.
